Primary Examiner—Sandra L. Morris*Assistant Examiner*—Mitchell I. Siegel*Attorney, Agent, or Firm*—Leonard Tachner[57] **CLAIM**

The ornamental design for “golf club cover configured as a sports item”, as shown and described.

DESCRIPTION

FIG. 1 is a side view of a golf club cover configured as a sports item, the undisclosed sides being identical;

FIG. 2 is a top plan view thereof; and,

FIG. 3 is a bottom plan view thereof.

The broken away pattern sections on the lower portion of the golf club cover is considered standard drawing practice.
